ATTORNEY

UNITED STATES PATENT OFFICE.

JOHN L. BATES, OF FRANKLIN, ARKANSAS.

WATER-WHEEL.

SPECIFICATION forming part of Letters Patent No. 224,128, dated February 3, 1880.

Application filed September 25, 1879.

To all whom it may concern:

Be it known that I, JOHN L. BATES, of Franklin, in the county of Izard and State of Arkansas, have invented certain new and useful Improvements in Water-Wheels; and I do hereby declare that the following is a full, clear, and exact description of the invention, which will enable others skilled in the art to which it appertains to make and use the same, reference being had to the accompanying drawings, and to letters of reference marked thereon, which form a part of this specification.

This invention relates to certain improvements in turbine water-wheels; and it has for its object to utilize the hydraulic pressure or head of the water derived from a suitable source or supply, and after this pressure has been fully exerted to utilize the weight of the water to exert additional power; and to this end my invention consists in a vertical shaft mounted or journaled in a suitable casing, and carrying two wheels, the upper one of which is provided with a series of radial blades and the lower one with a series of spiral blades, the casing being divided by a partial horizontal partition in such manner that the inflowing water will act on the upper wheel and the outflowing water on the lower wheel, as more fully hereinafter specified.

30 In the drawings, Figure 1 represents a top view of my improved apparatus with a portion of the casing broken away, and Fig. 2 a side elevation opened to illustrate the working parts of the wheel.

35 The letter A indicates the casing, which is made in two parts, *a* and *b*. *B* indicates a vertical shaft, journaled in bearings *c* *d* in the casing A.

40 The letter C indicates a series of radial blades secured to the upper part of the shaft B, and adapted to rotate in the upper part of the casing A, the said blades thus mounted constituting the upper wheel.

45 The letter D indicates the water-inlet, which may be connected with any suitable water-

supply in any convenient manner. Said water-inlet is provided with a gate, *e*, which is mounted on a suitable shaft extending through the top of the casing, and provided with gearing *g*, by which said gate may be opened or closed. The water-inlet leads into the upper portion of the casing A, the said upper portion being partially separated from the lower portion by means of a horizontal half-partition, *E*.

The letter G indicates a series of spiral blades secured to the shaft B in the lower portion of the casing A, the said casing being open at its bottom to provide for the ready escape of water.

50 The operation of my invention is as follows: Water being let in at the water-inlet enters the upper chamber in the casing formed by the half-partition and exerts its hydraulic pressure upon said wheel. Escaping, it reaches the point *h*, and falling upon the spiral wheel in the lower part of the casing, its weight causes said wheel to move in the same direction as the upper wheel, thus augmenting the power of the apparatus.

55 Having thus described my invention and its mode of operation, what I claim, and desire to secure by Letters Patent, is—

In a turbine water-wheel, the combined wheel consisting of a series of radial blades secured to the upper part of a vertical shaft mounted in a suitable casing, and a series of spiral blades mounted upon the lower part of said shaft, the casing being provided with a water-inlet in its upper part and an outlet at its bottom, and partially divided by a horizontal half-partition, substantially as and for the purposes specified.

60 In testimony that I claim the foregoing as my own I affix my signature in presence of two witnesses.

JOHN L. BATES.
